CLAIM

The ornamental design for an autoclave drain connector, as shown and described.

DESCRIPTION

FIG. 1 is a front plan view of the autoclave drain connector showing my new design.

FIG. 2 is a right side view thereof.

FIG. 3 is a back view thereof.

FIG. 4 is a top view thereof; and,

FIG. 5 is a bottom view thereof.

The broken lines shown in the drawings represent portions of the autoclave drain connector that form no part of the claim.

1 Claim, 4 Drawing Sheets(56)
